(57) **CLAIM**

The ornamental design for a castor, as shown and described.

DESCRIPTION

FIG. 1 is a frontal perspective view of my ornamental design;

FIG. 2 is a rear perspective view of the ornamental design of FIG. 1;

FIG. 3 is a side elevation view of the ornamental design of FIG. 1;

FIG. 4 is a top view of the ornamental design of FIG. 1;

FIG. 5 is a front plan view of the ornamental design of FIG. 1;

FIG. 6 is a rear plan view of the ornamental design of FIG. 1; and,

FIG. 7 is a bottom view of the ornamental design of FIG. 1. The broken lines in the drawing depict environmental subject matter only and form no part of the claimed design.
